UNITED STATES PATENT OFFICE.

OLOF OHLSON, OF WEST NEWTON, MASSACHUSETTS, ASSIGNEE TO WALTHAM WATCH COMPANY, OF WALTHAM, MASSACHUSETTS, A CORPORATION OF MASSACHUSETTS.

SETTING-STEM FOR WATCHES.

1,114,907.

Specification of Letters Patent.

Patented Oct. 27, 1914.

Application filed April 1, 1912. Serial No. 687,682.

To all whom it may concern:

Be it known that I, OLOF OHLSON, a citizen of the United States, and resident of West Newton, in the county of Middlesex and State of Massachusetts, have invented certain new and useful Improvements in Setting-Stems for Watches, of which the following is a specification.

This invention relates to an improvement 10 in the arrangement of the winding and setting stem of a watch in the frame of the watch movement and to an improvement in the means by which the stem is yieldingly held in either winding or setting position. 15 The object of the invention is to so dispose the holding or retaining means for this purpose in such a position that two important effects may be secured; first, a stem wound and set watch without a pendant may be 20 produced, and, secondly, the pendant of a pendant watch may be made with the least possible thickness so as to conform artistically to the proportions of thin watches.

With this object the invention consists of 25 the improvements which I will now describe and claim.

Two forms of watch both embodying the invention are illustrated in the accompanying drawings, one of them shown in Figures 30 1, 2, and 3 being a watch without a pendant adapted to be worn as a bracelet or locket watch. Fig. 1 is a partial front elevation of such a watch showing a part of the case and the crown. Fig. 2 is a cross section 35 on line 2—2 of Fig. 1. Fig. 3 is a view similar to Fig. 2 but showing the stem in a different position. Fig. 4 is an elevation similar to Fig. 1 showing a pendant watch in which the invention is incorporated. 40 Fig. 5 is a cross section on line 5—5 of Fig. 4. Fig. 6 is a view showing in elevation and in longitudinal section the improved retaining means for the setting stem or bar.

The same reference characters indicate 45 the same parts in all the figures.

In the drawings 1 represents the pillar plate or face plate, 2 represents one of the top plates or bridges, 3 the ring-shaped central part of the case, or "case center" as 50 it is called, 4 the back of the case, 5 the bezel in which the crystal is mounted, which forms the front cover of the case, 6 a winding and setting bar or stem, and 7 the crown which is screwed upon such bar and is 55 rotated in either winding the main spring

or setting the hands of the watch. The crown is screwed on the bar 6 in the usual way, and in Figs. 1, 2, and 3 such bar is shortened so that when in the winding position the crown is close to the case. This 60 allows the guard ring to extend only a slight distance from the case and enables the watch to be worn as part of a bracelet or in the manner of a locket.

The bar is movable endwise in being displaced from winding to setting position and vice versa, and is held in either of these positions by spring jaws 8 which embrace the bar and are adapted to lie on either side of a shoulder 9 on the latter. The faces 70 of this shoulder are beveled so that the lock afforded by the spring jaws is a yielding and not a positive one, whereby the bar may be moved by application of sufficient force upon the crown, although the jaws hold 75 the bar with sufficient firmness to prevent accidental displacement from either position. Preferably that side of the shoulder with which the jaws are engaged when the bar is in winding position is more steeply 80 beveled than the other side, in order to retain the bar more firmly in the winding position than it is retained in the setting position.

Preferably the spring jaws 8 are formed 85 by longitudinal cuts 10 in a sleeve 11 (shown in detail in Fig. 6), which sleeve has an inturned flange 12 on one end to form the active portions of the jaws, and an out-turned flange 13 on the other end 90 to afford a means for securing it in place. This out-turned flange is of such proportions and dimensions that it is gripped between a part of the case center and the plates 1 and 2 of the watch movement when 95 the latter is in the case, as shown in the sectional views. Preferably the part of the case which engages the flange 13 is a tube or sleeve 14 passing radially through the case center and secured immovably therein 100 with its inner end engaging the flange. Its outer end projects beyond the circumference of the case and extends for some distance into an annular groove 15 in the crown surrounding that portion of the latter which 105 is engaged with the bar 6. The purpose of the sleeve 14 is to protect the bar and jaws, avoiding exposure thereof even when the crown and bar are pulled out to their fullest extent. A square shoulder 16 on the bar 110

limits the amount of outward motion permitted to the bar, preventing the bar being entirely withdrawn and arresting the same before the crown passes beyond the end of the sleeve 14.

The essential features of the invention are the same when applied to a pendant watch of the sort shown in Figs. 4 and 5. The only important differences are that the 10 winding and setting bar is provided with an extension 6^a of any desired length, which is incased in a pendant 17. The latter has a foot portion 18 which passes through the case center in a substantially radial manner 15 and is secured therein, performing the same function as the sleeve 14, cooperating with the movement frame to grip the base flange of the retaining device. On the outer end the pendant has a sleeve 19 entering the 20 groove 15^a of the crown 7^a. Adjacent to the crown the pendant is provided with bosses 20 of usual character and form to hold the ends of the guard ring or bow 21. The pendant is in effect the same as the sleeve or 25 tube 14 being simply elongated and having means for the attachment of a guard ring.

The resilient retaining means may be considered as a set of jaws which are detachably gripped at their base-portion between the 30 periphery of the movement-frame and the adjacent part of the case center and their active or operative ends extend outwardly from their points of attachment. This construction enables the retaining means to be 35 located, to all intents and purposes, entirely within the outer circumference of the case.

Consequently in the case of a watch, such as shown in Figs. 1, 2, and 3, it is possible to bring the crown so close to the case as to 40 be practically in contact with it, while in the case of the pendant watch, the pendant may be made much narrower than has heretofore been possible. The extent to which the pendant may be narrowed is limited only by the 45 thickness of the winding bar, and the latter requires to be only thick enough to sustain the power of the main spring in winding without twisting. That is, the pendant need not be large enough in its shorter diameter to admit any other parts than the bar alone and consequently it may be designed 50

in artistic proportion to the thinnest of thin watches. When the movement is removed from the case, the bar retainer is prevented from falling out by its engagement with the shoulder 16 of the bar, but the retainer and bar can be readily removed together upon unscrewing the crown from the outer end of the bar.

I claim:

1. In a watch the combination of a case having an annular center, a sleeve passing radially through said case center and secured immovably thereto, a movement fitting in said case center, a winding and setting bar passing through said sleeve into connection with the movement and having a shoulder with inclined faces, and a retainer for said bar having a base flange gripped between the inner end of the sleeve and the 70 movement, and having spring jaws within the sleeve embracing said bar and arranged to engage the shoulder thereof, the outer limits of said jaws being substantially in the outer circumference of the case center. 75

2. In a watch the combination of a case having an annular center, a sleeve passing radially through said case center and secured immovably thereto, a movement fitting in said case center, a winding and setting bar passing through said sleeve into connection with the movement and having a shoulder with inclined faces, and a retainer for said bar consisting of a sleeve located within the first-named sleeve and surrounding the bar, 80 having an out-turned flange on its inner end underlying the inner end of the first sleeve and gripped between the latter and the movement, and having an inturned flange and being longitudinally cut on its outer end to 85 provide spring jaws adapted to engage the shoulder of the bar, the length of said retainer being approximately equal to the radial distance between the inner and outer circumferences of the case center. 90

In testimony whereof I have affixed my signature, in presence of two witnesses.

OLOF OHLSON.
